PIETRO MAGNI, OF GENOA, ITALY.

DRIVING APPARATUS FOR HIGH-SPEED LOCOMOTIVE CRAFT.

Application filed June 10, 1926, Serial No. 115,148, and in Great Britain July 22, 1925.

My present invention has for its object to provide an improved driving apparatus for aerial and other craft comprising a suitable air-cooled internal combustion engine designed for driving a propeller screw, a set of chests or casings, suitable deviators and special ventilators as will be described hereafter, for the purpose of rendering the air-cooled internal combustion engine more especially adapted for air craft and generally for high speed locomotion by greatly diminishing the resistance to penetration of the craft (aeroplane, hydroplane or motor driven by aerial propellers) into its surrounding fluid, at the same time providing the motor cylinders with a cooling air current of considerable speed and efficiency.

By way of example I have illustrated my invention in the accompanying drawing which shows a longitudinal section of my improved driving apparatus applied to the body of an aeroplane; *a* is the aeroplane body, *b* the air-cooled (starlike) engine, *c* the propeller screw, *d* the chest or casing in the place reserved for the engine, *e* the outlet apertures for the cooling air, *f* the chest of casing in the place where the propeller screw is mounted (i. e.: covering the drum of the rotating screw), *g* the ogival or penetrating casing provided at its vertex with a hole *h* and forming the head of the penetrating system consisting of the body of the aeroplane with the casings, *i* a deviator placed in front of the hub of the propeller screw and designed for leading the air absorbed by the ventilators towards the cylinders and the most heated parts of the engine, *k* the ventilators mounted on the drum of the propeller screw and rotating with the latter, *l* a diagram of the air current in which the craft is emersed, which for the sake of clearness has been omitted in the lower half of the sectional view, *m* an annular outlet tube for the exhaust gases, so placed as to be swept by the internal or external air current, and *n* a movable window capable of increasing or diminishing or even closing completely the annular aperture *e*.

Such driving apparatus system as described may be of course applied to any body or carlin of whatever section.

The internal combustion engine designed for driving the craft, as is seen from the above, is partially or totally enclosed in an

ogival chest or casing divided into a number of segments or rings some of which are fixed to the body of the aeroplane and some to the propeller screw with which latter they rotate.

The outline of the said chest gradually becomes ogival, starting from a hole in the vertex of the air penetrating ogive and being continued possibly without interruption up to the top of the body, there forming an annular outlet conduit for the air current. This conduit is continuous or interrupted for certain lengths according to the practical possibilities and provided with a movable window controlled by the pilot during the flight, permitting him to increase or diminish the final section of said outlet and consequently to regulate the quantity of cooling air compelled to sweep the motor.

The air is compelled to penetrate and pass into the interior of the head formed by said chest through the comparatively small front hole by one or more ventilators fixed to the drum of the propeller screw and led by suitable deviators to sweep past the motor cylinders before leaving the apertures.

Having now particularly described and ascertained the nature of my said invention and in what manner the same is to be performed, I declare that what I claim is:

Improvements in driving apparatus for high speed locomotive craft comprising an internal combustion engine partially or totally enclosed in an ogival chest divided into a number of segments, some of which fixed to the body of the aeroplane and some to the propeller screw with which latter they rotate, the outline of said chest gradually becoming ogival, starting from a hole in the vertex of the air penetrating ogive and being continued, possibly without interruption, up to the top of the body there forming an annular outlet conduit for the air current, a ventilator fixed to the drum of the propeller screw to compel air to penetrate and pass through the front hole, deviators to lead air past the motor cylinders, a moveable window controllable by the pilot during the flight to regulate the quantity of cooling air compelled to sweep the motor.

In testimony whereof I have hereunto signed my name.

PIETRO MAGNI.
